(57) **CLAIM**

I claim the ornamental design for a spin bag bracket, as shown
and described.

DESCRIPTION

FIG. 1 is a perspective view of a spin bag bracket, showing my
new design;

FIG. 2 is a front elevational view of the invention;

FIG. 3 is a rear elevational view of the invention;

FIG. 4 is a left-side elevational view of the invention, the
right-side elevational view being a mirror image thereof;

FIG. 5 is a bottom plan view of the invention; and,

FIG. 6 is a top plan view of the invention.

The broken line showing a suspended punching bag in the
Figures is included for the purpose of illustrating the invention
in use, and forms no part of the claimed design.
